UNITED STATES PATENT OFFICE.

PETER MCLEOD, OF GLASGOW, SCOTLAND.

CURLING STONE.

Application filed November 23, 1926, Serial No. 150,288, and in Great Britain November 27, 1925.

This invention relates to curling stones, its object being to provide means whereby said stones can be used for playing on surfaces other than ice.

To the attainment of this object, according to the present invention, the bearing surface of the stone is formed by one or more pieces of wax or like substances (hereinafter referred to for convenience as "wax"). The curling stones are preferably used on a glass or other rink whose surface offers little resistance to the stone, said surface being preferably kept moist by water or other suitable liquid.

The wax may be carried in the stone itself or in a member adapted to be secured to the stone or in both of these and means may be provided whereby the wax may be fed forward in order to replace that which is worn away while the stone is being used. The wax may, for example, be arranged in spaced apertures in a member adapted to be detachably secured to the stone by means of the existing bolt, which is also used for securing the handle to the stone, or the wax may be arranged in arcuate apertures in said member, or otherwise, as desired.

Means may also be provided on the stone whereby the surface of the glass or other rink is kept continually moistened, and said means may consist of a fringe or ring of fabric attached to the stone and adapted, in the flight of the stone over the rink, to contact with the surface of the latter and to impart moisture, carried by said fabric, thereto.

It will be understood that where the wax is carried in a member adapted to be secured to the stone that this member may either be permanently fixed to and sold with the stone or it may be sold separately for application to existing stones.

Two constructions of curling stones are illustrated by way of example upon the accompanying drawings wherein:—

Fig. 1 is a sectional elevation of one construction.

Fig. 2 is an inverted plan thereof.

Fig. 3 is a section on line III-III in Fig. 1.

Fig. 4 is a sectional elevation of the second construction.

Fig. 5 is an inverted plan thereof.

In one constructional form of my invention a wooden plate 1 is secured to the underside of the curling stone 2 by means of

the existing bolt marked 3 of the curling stone. The bolt 3 is that which normally serves to secure the handle 4 to the curling stone. Holes 5 are drilled in the wooden plate and in these holes are located bushes 6. The wax preferably in the form of a cylindrical block is inserted into each of the holes formed in the wooden plate. On top of the wax is mounted a stud 8 which is slidable in the bush 7 and has a projection 9 with an inclined upper surface 9a. This inclined surface of the projection cooperates with inclines 10 on the ring 11 rotatably mounted in the groove 12 in the underside of the wooden plate. A metal disc 13 is mounted on the inner side of the wooden plate between the wooden plate and the stone and the ring is provided with a laterally extending operating handle 16 either formed integral with the ring or formed separately thereof and secured to the ring. This handle is provided with a projection 14 adapted to engage in the notches 15 of a rack-like periphery formed on the plate 13 at one side thereof and the handle is made of some resilient material and is so arranged as normally to retain the projection 14 in engagement with the notches 15.

The ring and the studs are so arranged that by retracting the handle from engagement with the notches 15 and rotating the ring the studs are moved downwardly so as to feed the wax. After the wax has been fed so as to project to the desired extent below the wooden plate the handle is released when it moves into engagement with one of the notches 15 and thereby retains the parts in their adjusted positions. Although in the construction illustrated I have shown projections and inclined surfaces both on the studs and on the ring it will be understood that such projections may be provided on the ring or on the studs only if the parts are so arranged that on rotation of the ring the desired movement of the studs will be obtained. Further it will be understood that in place of the ring a plate may be employed.

In the construction shown in Fig. 4 a curling stone 20 is made as a hollow member preferably of cast iron. This hollow member has an opening 21 at its upper end across which projects a handle 22. In this case as in the previous construction a wooden plate 23 is employed secured

to the underside of the hollow member. Moreover tubular members 24 are provided at spaced intervals said tubular members passing almost completely through the wooden plate and extending through the underside wall of the hollow member into the interior thereof. These tubular members 24 serve to receive the wax which, as before, is in the form of cylindrical bars and moreover these tubular members are each provided with a plunger 26 mounted upon a common yoke 27 and operated by the wing nut 28 and screw 29 so as to feed the wax.

15 As will be seen from the drawing the wax is caused to slightly project below the under surface of the wooden plate so as to form a bearing surface for the stone. After the curling stone has been in use for some time however the ends of the pieces of wax become worn and the wax then requires to be fed as aforesaid.

20 It will be understood that the wooden members can be dispensed with and the wax be carried directly by the stone itself.

25 The curling stone is used on a glass rink, whose surface is kept continually moistened by means of a fabric fringe or ring 30 which is secured to the underside of the curling stone or to one plate 1 or 23 and is dipped into water or other suitable liquid. The fringe is of such a length that when the curling stone is in flight the end of said fringe contacts with the surface of the rink 30 so as to keep it moist. The brushes which are used in the game are also kept wet so as to assist in moistening the surface of the rink.

40 The combination of the wax bearing surface on the curling stone with the wetted surface of the glass rink causes the curling stone to move quickly and with little friction thereover, so that the conditions of the game are almost the same as if the curling stone was being used on an ice rink.

45 The invention may be applied to any existing form of curling stone, and the wax may be replaced by any suitable wax-like substance. In some cases when my improved curling stones are used on a glass rink I may provide the latter with a portion or boundary of rustless steel or other suitable material, at those places where the curling stones are flung by the players.

50 I claim:

1. A curling stone having one or more pieces of wax secured on its lower surface adapted to form a bearing for the stone.
2. A curling stone having pieces of wax carried in the stone adapted to project below the lower surface of the stone to form a bearing therefor and means for feeding the wax as it is worn away.
3. A curling stone having a member secured to the underside thereof having re-

cesses therein, pieces of wax in said recesses arranged to project below the base of said member to act as a bearing for the stone.

4. A curling stone having one or more pieces of wax secured on its lower surface 70 adapted to form a bearing for the stone and means on said stone whereby the playing surface is moistened.

5. A curling stone having pieces of wax carried in the stone adapted to project below the lower surface of the stone to form a bearing therefor, means for feeding the wax as it is worn away and means on said stone whereby the playing surface is moistened. 75

6. A curling stone having a member secured to the underside thereof having recesses therein, pieces of wax in said recesses arranged to project below the base of said member to act as a bearing for the stone and means on said stone whereby the play- 80 ing surface is moistened. 85

7. A curling stone having one or more pieces of wax secured on its lower surface adapted to form a bearing for the stone and a fringe of fabric attached to said stone 90 adapted to contact with the playing surface and impart moisture carried by the fabric thereto.

8. A curling stone having pieces of wax carried in the stone adapted to project below the lower surface of the stone to form a bearing therefor and means for feeding the wax as it is worn away and a fringe of fabric attached to said stone adapted to contact with the playing surface and impart moisture carried by the fabric thereto. 95

9. A curling stone having a member secured to the underside thereof having recesses therein, pieces of wax in said recesses arranged to project below the base of the 105 member to act as a bearing for the stone and a fringe of fabric attached to said stone adapted to contact with the playing surface and impart moisture carried by the fabric thereto. 110

10. A curling stone having means for carrying wax, pieces of wax in said carrying means adapted to project below the lower surface and form a bearing for the stone, means for supporting the inner end 115 of said pieces of wax, a rotatable member, inclined surfaces on said member adapted on rotation of said member to force said supporting means outwardly so as to feed said pieces of wax and means for rotating said member. 120

11. A curling stone having means for carrying wax, pieces of wax in said carrying means adapted to project below the lower surface and form a bearing for the stone, means for supporting the inner end 125 of said pieces of wax, a rotatable member, inclined surfaces on said member adapted on rotation of said member to force said supporting means outwardly so as to feed said 130

pieces of wax, means for rotating said member, and means on said stone whereby the playing surface is moistened.

12. A curling stone having means for carrying wax, pieces of wax in said carrying means adapted to project below the lower surface and form a bearing for the stone, means for supporting the inner end of said pieces of wax, a rotatable member, inclined surfaces on said member adapted on rotation of said member to force said supporting means outwardly so as to feed said pieces of wax, means for rotating said member, and a fringe of fabric attached to said stone adapted to contact with the playing surface and impart moisture carried by the fabric thereto. 60

13. A curling stone having means for carrying wax, pieces of wax in said carrying means adapted to project below the lower surface and form a bearing for the stone, means for supporting the inner end of said pieces of wax, a rotatable member, inclined surfaces on said member adapted on rotation of said member to force said supporting means outwardly so as to feed said pieces of wax, a laterally extending operating handle on said member and a rack co-operating with said handle to retain it in its adjusted position. 70

14. A curling stone having means for carrying wax, pieces of wax in said carrying means adapted to project below the lower surface and form a bearing for the stone, means for supporting the inner end of said pieces of wax, a rotatable member, inclined surfaces on said member adapted on rotation of said member to force said supporting means outwardly so as to feed said pieces of wax, a laterally extending operating handle on said member, a rack co-operating with said handle to retain it in its adjusted position, and means on said stone whereby the playing surface is moistened. 75

15. A curling stone having means for carrying wax, pieces of wax in said carry-

ing means adapted to project below the lower surface and form a bearing for the stone, means for supporting the inner end of said pieces of wax, a rotatable member, 50 inclined surfaces on said member adapted on rotation of said member to force said supporting means outwardly so as to feed said pieces of wax, a laterally extending operating handle on said member, a rack co-operating with said handle to retain it in its adjusted position, and a fringe of fabric attached to said stone adapted to contact with the playing surface and impart moisture carried by the fabric thereto. 60

16. A curling stone comprising a hollow body having holes in the underside thereof, pieces of wax in said holes and means in said body for feeding said pieces. 65

17. A curling stone comprising a hollow body having holes in the underside thereof, pieces of wax in said holes, plungers in the inner ends of said holes adapted to support and feed said pieces and means for moving said plungers. 70

18. A curling stone comprising a hollow body having holes in the underside thereof, pieces of wax in said holes, plungers in the inner ends of said holes adapted to support and feed said pieces, a yoke connecting said 75 plungers and a screw device for moving said yoke and plungers.

19. A curling stone comprising a body part, a member on the underside of said body part having holes therein, means for 80 securing said member to said body part, pieces of wax in said holes, studs in the inner ends of said holes, a plate rotatably mounted between said member and said body part, means on said plate adapted to 85 engage with and feed said studs on rotation of said plate, means for operating said plate and means for retaining said plate in its adjusted position.

In testimony whereof I affix my signature.

PETER McLEOD.
